UNITED STATES PATENT OFFICE.

MERLE J. WEST, OF MILWAUKEE, WISCONSIN, ASSIGNOR, BY MESNE ASSIGNMENTS,
TO H. W. LE MAHIEU, OF OOSTBURG, WISCONSIN.

SWITCH.

Application filed March 10, 1921. Serial No. 451,153.

To all whom it may concern:

Be it known that I, MERLE J. WEST, a citizen of the United States, and resident of Milwaukee, in the county of Milwaukee and 5 State of Wisconsin, have invented new and useful Improvements in Switches, of which the following is a description, reference being had to the accompanying drawings, which are a part of this specification.

10 The invention relates to circuit closers.

The general object of the invention is to provide a circuit closer of simple, compact and strong construction.

15 A further object of the invention is to provide a circuit closer having an exposed pad forming part of the movable contact so that the circuit may be readily closed by pressing on it with the whole hand, a desirable feature where the closer is used in an alarm 20 circuit.

The invention further consists in the several features hereinafter set forth and more particularly defined by claims at the conclusion hereof.

25 In the drawings: Fig. 1 is a front elevation view of a device embodying the invention; Fig. 2 is a side elevation view of the device; Fig. 3 is a section taken on the line 3—3 of Fig. 1; Fig. 4 is a front view of the 30 device with the cover removed; Fig. 5 is a detail view of the movable contact.

A metal base member 6 is provided with a terminal-receiving recess 7 having a side opening 8, one end 9 of this recess being 35 higher than the other portions of the recess. This member has holes 10 in its ends to receive screws or other suitable fastening means securing the closer to a suitable support.

40 One of the current-carrying wires 11 is secured to the member 6 by a terminal screw 12 and the other wire 13 is secured by a terminal screw 14 to a bushing 15 of insulating material mounted in the member 6. The 45 wires 11 and 13 are led into the recess 7 through the opening 8.

A movable resilient contact member 16 has one end fixedly secured to the member 6 at the end 9 of the recess 7 by means of screws 50 17, and a key slot 18 is formed near the other end of this member.

A pad 19 of metal or other suitable material has its base portion 20 designed to fit the recess 7 and is provided with a button 21 for attaching it to member 16 by interlocking engagement with the slot 18, the head of the button being passed through the enlarged portion 18' of the slot 18 and the pad then moved to bring the shank of the button into the narrow portion of the slot 18, as indicated in Fig. 3.

With this construction, pressure upon the lower end of the pad 19 moves the member 16 into contact with the head of the screw 14 to complete the circuit, and this pad having 65 a large exposed surface permits the operator to easily direct his hand or elbow against it for closing the circuit quickly, as in the case of sending in an alarm. The pad 19 and member 16 are readily removable from 70 the base member 6 so that the circuit connections may be easily made.

What I claim as my invention is:

1. In a circuit closer, the combination of a metal base member having a recess with an 75 elevated end and a conductor passage leading to the recess, a resilient contact plate having one end secured to said elevated end and having a key slot in its other end, and actuating pad fitting within the recess and 80 having a button cooperating with said slot to secure the pad to said plate, a terminal connector in said recess in circuit with the base member, and an insulated terminal connection in said recess adapted to be engaged by said plate.

2. In a circuit closer, the combination of a metal base member having a recess, binding posts for securing the ends of the conductor wires within said recess, one of said posts 90 being insulated from said member, a resilient plate within the recess and detachably secured at one end to said base member and having its free end movable into contact with said insulated binding post, an actuating 95 pad having its base fitting in said recess, and a detachable slip-on interlocking connection between said pad and plate.

In testimony whereof, I affix my signature.

MERLE J. WEST.
